ABSTRACT

In apparatus for reproducing multichannel sound signals, a system is provided for restoring a four-channel signal, derived from a two-channel sound source, to its two-channel condition, to produce two signals which are free of the additional two signals.

3 Claims, 1 Drawing Figure

**METHOD AND APPARATUS FOR THE
PRODUCTION OF MULTICHANNEL SOUND
SIGNALS**

BACKGROUND

1. Field of the Invention

The present invention relates to a method and apparatus for producing multichannel sound signals, and more particularly, to a system for restoring a properly balanced stereo signal from a four-channel signal derived from an original stereo signal.

2. The Prior Art

The recent popularity of quadraphonic techniques in sound recording and reproduction has led to the availability of a number of four-channel recordings which are derived originally from two-channel sources. The four-channel recordings are derived from the two original sound channels by modifying the normal left and right signals to produce two additional signals which are typically used as the left rear signal and the right rear signal, when the signals represent four corners of a quadrilateral. This is done in such a way that the four-channel signal may be employed compatibly with normal stereo (two channel) equipment. When the four-channel signals are reproduced with two-channel equipment, the two additional channels of the four-channel signals are automatically combined on the normal left and right stereo channels to form composite left and composite right signals. This combination sometimes leads to a drastic deterioration in the sound produced by the two stereo channels, which is extremely undesirable.

SUMMARY OF THE PRESENT INVENTION

It is a principal object of the present invention to provide a system for restoring the separation and balance of two-channel signals from four-channel signals which have been derived therefrom.

Another object of the present invention is to provide a simple means of accomplishing the aforesaid result.

These and other objects and advantages of the present invention will become manifest by examination of the following description and the accompanying drawing.

In one embodiment of the present invention, there are provided means for producing four signals corresponding to the four channels of a quadraphonic sound source, means for mixing signals from two of the four channels to produce a reconstituted left two-channel signal, and means for mixing signals from the other two of said four channels to produce a reconstituted right two-channel signal.

BRIEF DESCRIPTION OF THE DRAWINGS

Reference will now be made to the accompanying drawing, which is a functional block diagram of a system incorporating the present invention.

**DESCRIPTION OF THE PREFERRED
EMBODIMENT**

Referring to the drawing, a quadraphonic sound source 5 is illustrated having four output lines, 1, 2, 3, and 4. The output line 1 is for the left front signal, the output line 2 is for the right front signal, the output line 3 is for the left rear signal, and the output line 4 is for the right rear signal. When quadraphonic reproduction

is desired, these four output signals are applied respectively to the loudspeakers 6, 7, 8, and 9, in order to reproduce quadraphonic sound in the customary manner.

When it is desired to reproduce the original two-channel stereo signal from which the quadraphonic signal is derived, the normal practice is to combine the signals on the left output lines 1 and 3 into a single output and the signals on the right output lines 2 and 4 into another output. However, this is not satisfactory in retaining the original stereo signal.

By means of the present invention, the original left channel signal is restored by mixing a portion of the signal available on the output line 3 with the signal produced at the output line 1. A level control 10 is pro-

vided for selecting a portion of the signal available on the output line 3 and connecting it to the loudspeaker 6, in common with the output line 1 from the source 5. A phase inverter 11 is interposed between the level control 10 and the loudspeaker 6, in order to invert the phase of the signal.

A similar level control 12 is provided for the right channel, and functions to mix a portion of the signal provided on the output line 4 with the signal provided on the output line 2 and to apply it to the loudspeaker 7.

A phase inverter 13 is interposed between the level control 12 and the loudspeaker 7 to invert the phase of the signal.

It can be seen that, by means of the level controls 10 and 12, a selected portion of the signals on the output

lines 3 and 4 may be added to the signals on the output lines 1 and 2. By operation of the phase inverters 11 and 13, the signals selected by the level controls 10 and 12 are, in effect, subtracted from the signals present on the outputs 1 and 2. When the level control 10 is ad-

justed so that the signal available at the output of the inverter 11 has components corresponding in amplitude to the components of the signal present on the output line 3, but opposite in phase, these components cancel each other out and form a new signal for applica-

tion to the loudspeaker 6. Thus, the disturbing compo-

nents are removed, restoring the original two-chan-

nel signal to the loudspeaker 6. The same is true of the signal applied to the loudspeaker 7 when the level con-

trol 13 is properly adjusted. If desired, the loudspeakers

8 and 9 may be disconnected, so that two-channel

sound is produced only by the loudspeakers 6 and 7.

The phase inverters 11 and 13 are preferably amplifiers having unity gain, with the output of the amplifiers being the inverse of the input, so that the frequency and

phase relationship of the signals are not modified ex-

cept to invert the phase thereof. The level controls 10

and 12 may take the form of T pads or L pads, or alter-

nately, may comprise amplifiers having manually ad-

justable gains. Such devices are well known in the art

and therefore need not be described in detail herein.

When a phase inversion of the signals derived from

the output lines 3 and 4 is not desired, the inverters 11

and 13 may be omitted from the circuit. It is apparent

that a great variety of different level signals may be pro-

vided by manipulation of the level controls 10 and 12,

with the inclusion or omission of the phase inverters 11

and 13. The desired proportions of signals which are

mixed in order to restore the original stereo signals are

readily chosen by the operator, in accordance with his

preferences.

What is claimed is:

1. A method of restoring two channel signals of a

two-channel signal source by modifying the right front

and left front signals of a four-channel source having individual channels for the left front signal, the right front signal, the left rear signal, and the right rear signal, such four signals having been derived from signals of said two-channel source, comprising the steps of: selecting a first portion of the left rear signal, inverting said first portion to produce a first inverted signal, and mixing only said first inverted signal with said left front signal for modifying said left front signal, selecting a second portion of the right rear signal, inverting said second portion to produce the second inverted signal, and mixing only said second inverted signal with said right front signal to produce a modified right front signal, whereby said modified left front and right front signals restore the signals of said two-channel source.

2. Apparatus for restoring two channel signals of a two-channel signal source by modifying the left front and right front signals of a four-channel source having separate channels for the left front signal, the right front signal, the left rear signal, and the right rear sig-

nal, such four signals having been derived from signals of said two-channel source, comprising means for selecting a first portion of said left rear signal, means for inverting said first portion to produce a first inverted signal, means for mixing said first inverted signal with said left front signal to produce a modified left front signal, means for selecting a second portion of said right rear signal, means for inverting said second portion to produce a second inverted signal, and means for mixing only said second inverted signal with said right front signal to produce a modified right front signal, whereby said modified left front and right front signals restore the signals of said two-channel source.

3. Apparatus according to claim 2, including a first variable resistor interconnected between said left front and left rear signals and a second variable resistor interconnected between said right front and right rear signals.
